MACHINE FOR SEPARATING SHOES FROM
LASTS

Joseph Harrington, Jr., Wenham, Mass., assignor
to United Shoe Machinery Corporation, Paterson, N. J., a corporation of New Jersey

Application June 7, 1937, Serial No. 146,800

21 Claims. (Cl. 12—15.1)

This invention relates to machines for separating shoes from lasts and is herein illustrated and described as embodied in a treadle-operated machine having a member which engages the rear portion of a shoe and forces it off the last. It is an object of the present invention to provide an improved machine of the character under consideration.

In accordance with a feature of the invention, and as herein illustrated, the member which engages the rear portion of a shoe and another member which is engageable with the forepart of the sole of the shoe are both mounted upon a carrier which is operated to cause the first-mentioned member to raise the rear portion of the shoe relatively to the last and to cause the second-mentioned member to break the last by pressure applied through the forepart of the sole of the shoe. In the illustrated construction the member which engages the rear portion of the shoe comprises a friction pad and both members are mounted upon a lever having its fulcrum coaxial with the hinge of the last, so that as the friction pad is being moved in one direction to raise the rear end of the shoe the sole-engaging member will be moved in the opposite direction to break the last. In accordance with a further feature the fulcrum support of the above-mentioned lever is movable to enable the lever to move forwardly with respect to the shoe after the rear portion of the shoe has cleared the last so that the friction pad may urge the shoe forwardly off the last.

These and other features of the invention comprising certain combinations and arrangements of parts will be apparent from the following description of a preferred embodiment of the invention shown in the drawings, in which

Fig. 1 is a side elevational view of the upper portion of the improved machine;

Fig. 2 is a side elevational view of the lower portion of the machine;

Fig. 3 is a plan view of the machine; and

Fig. 4 is a view in end elevation of a portion of the machine looking in the direction of the arrow A of Fig. 3.

As shown in Figs. 1 and 2, the supporting structure of the machine consists of a frame 10 adapted to rest upon the floor and carrying a head 12 having a horizontal shelf 14. Secured upon the upper surface of the shelf 14 by clamping screws 16 is a block 18 in which is mounted in an upstanding position a last pin 20. The last pin, which is threaded into the block 18 to provide for heightwise adjustment, has an integral

hexagonal collar 21 to facilitate turning, and is secured in adjusted position by a lock nut 114. The block 18 is provided with a pair of longitudinal slots 22 through which the screws 16 extend so as to provide for adjustment of the position of the last pin forwardly and rearwardly.

Pivotedly mounted upon a pin 24 in the head 12 is a link 26. A pin 28 rotatably mounted in the upper end of the link 26 constitutes a fulcrum for a lever 30 into which the pin 28 is threaded. The lever 30 which extends forwardly and rearwardly of the machine and is positioned to one side of the last pin 20, serves as a carrier for the shoe-engaging members presently to be described. The lever 30 is normally supported in a horizontal position by a stationary abutment 32 extending upwardly from the head 12, and is held against the abutment 32 by a spring latch 34 which engages a notch 36 formed in the abutment. Formed in the lever 30 rearward of the fulcrum 28 and on the inner side of the lever, which is the side adjacent to the last pin 20, is a longitudinal guideway 38 in which is mounted a slide block 40. A pair of plates 42 secured to the lever 30 and extending partially over the guideway 38 retain the slide block 40 within the guideway. Extending from the slide block 40 is an arm 44 upon which is mounted a metal holder 46 for a U-shaped rubber pad 48 adapted to engage the rear portion of a shoe upper. The holder 46 is retained upon the arm 44 by a pair of screws 50 threaded into the arm and having washers 51 extending over the upper surface of the pad-holder. The screws 50 do not clamp the holder 46 to the arm 44 but afford a limited freedom of lateral movement as the pad 48 engages the shoe, the holder 46 being provided with laterally elongated openings 52 through which the screws 50 extend.

Fulcrumed upon a pin 54 secured in the forward portion of the lever 30 is a bellcrank 56 having an upwardly extending arm connected to the slide block 40 by a rod 58. The other arm of the bell crank 56 is connected by a downwardly extending rod 60 to a treadle 62 fulcrumed upon a pin 64 secured in the lower portion of the frame 10. The treadle 62 is normally held up by a tension spring 66 having its upper end anchored upon a screw 68 secured in the head 12. This same screw 68 is employed also as a set screw to secure the pin 24 in the head 12. The upward limit of movement of the treadle 62 is determined by the upper edge of an opening in the frame 10 through which the

treadle extends (Fig. 2). Downward movement of the treadle 62 is limited by an adjustable stop 70 in the lower portion of the frame 10. A tension spring 72 having one end secured to the bell crank 56 and its opposite end anchored to the lever 30 tends to maintain the slide block 40 at the rearward end of the slide 38.

A sleeve 76 having a knurled head 78 to facilitate its adjustment is threaded into a block 74 mounted upon the outer side of the lever 30. Journaled in the sleeve 76 and retained therein against axial movement by collars 79 is a pin 83. Extending radially from a hub 81 secured upon the pin 80 is an arm 82 the outer end portion 84 of which is in the form of a wedge-shaped block having an inclined lower face (Fig. 1). This inclined lower face of the block 84 is covered by a rubber pad 86 the ends of which are secured to the upper surface of the block 84 by screws 87 and clamping strips 89. A relatively weak tension spring 88 having one end secured to the arm 82 and its other end anchored to the lever 30 tends to urge the arm 82 in a clockwise direction, as viewed in Fig. 3, or rearwardly with respect to a shoe on a last supported by the last pin 20. Such rearward movement of the arm 82 is limited by an arm 90 extending from the upper collar 79 which, in turn, is secured to the pin 80, the arm 90 having a downward extension 92 which engages the block 74. In order to provide for longitudinal adjustment of the block 74 on the lever 30 the block has formed in it longitudinal slots 94 through which extend screws 96 which clamp the block to the lever.

The link 26 is urged rearwardly by a tension spring 97 having one end secured to the link and its other end anchored to a pin 98 extending from the head 12. A lug 100 which also extends from the head 12 carries a rubber bumper 102 which serves as an abutment for an extension 104 on the link 26. The bumper 102 is so positioned upon the head 12 that when the link 26 is held thereagainst by the spring 97 the latch 34 will engage the notch 36.

Forward swinging movement of the link 26 is limited by a hook 106 adjustably threaded into the head 12. Threaded into a lug 108 formed on one side of the link 26 is a stop screw 110 which is engageable with the under surface of the lever 30 to limit downward tilting movement of the lever as shown in Fig. 1. The screw 110 is secured in any desired position of adjustment by a lock nut 112.

In operating the machine a last L having a shoe S thereon is mounted in inverted position upon the last pin 20. The weak spring 88 yields readily to enable the operator to push the padded block 84 out of the way, which he usually does with the wrist of the hand grasping the shoe. As soon as he has finished mounting the last and shoe upon the last pin the spring 88 will bring the pad 86 into engagement with the tread surface of the sole. It will be noted that the pad 86 is self-adjusting, inasmuch as it will automatically find its proper operating position regardless of the size of the shoe or the slope of the sole. The under surface of the block 84 has a slope generally similar to that assumed by the sole of a shoe about to be operated upon, insuring an adequate area of contact between the pad and the sole and also, by reason of the wedging action of the pad, insuring firm contact between the pad and the sole notwithstanding the weakness of the spring 88. The block 18 should be adjusted (for the first shoe of each lot) to the

right or left, as viewed in Fig. 1, so as to bring the hinge of the last L substantially into alignment with the axis of the fulcrum 28. The last pin 20 should also be adjusted heightwise to bring the rear portion of the shoe upper into proper relation to the pad 48.

The operator now depresses the treadle 62, causing a downward pull on the rod 60. This tends to tilt the lever 30 and thus gives rise to a heightwise component of force tending to move the friction pad 48. It also operates through the bell crank 56 to set up a forward component of force acting upon the pad 48. Immediate tilting of the lever 30 about its fulcrum 28 is prevented by the spring latch 34. The first effect, therefore, of the pull in the rod 60 is to rotate the bell crank 56 in a clockwise direction, as viewed in Fig. 1, until the friction pad 48 engages the rear portion of the shoe upper, further rotary movement of the bell crank thus being arrested. The pad 48 thus finds its proper operating position regardless of the size of the shoe. The downward pull of the rod 60 acting through the bell crank fulcrum 56 thereupon tends with increasing force to tilt the lever 30 in a clockwise direction about its fulcrum 28, such tilting being resisted, however, by the spring latch 34 until the pad 48 has developed an adequate frictional gripping pressure against the rear of the shoe upper. The latch 34 then yields, enabling the lever 30 to tilt. As the friction pad 48 rises it carries the rear portion of the shoe upwardly off the last while at the same time the pad 86 bears downwardly upon the tread surface of the forepart of the sole of the shoe and thereby breaks the last. The shoe-engaging members thus operate in unison, each to aid the other. As the pad 48 moves upwardly it will still be held against the rear of the shoe by pressure on the treadle and, being movable relatively to the lever 30, it will not be constrained to travel in a path concentric with the fulcrum 28 but will be free to follow the heightwise curvature of the rear end of the last. The path of travel of the pad 48 during this portion of the operation will thus be determined by the shape of the last.

The stop screw 110 should be so adjusted as to engage the lever 30 and thereby to prevent further tilting movement as soon as the rear end of the shoe upper has cleared the last. The last by this time will have snapped into broken position, and the pad 86 will no longer bear against the shoe bottom, or at least will not exert any considerable degree of pressure thereagainst. The block 84 is now free to swing downwardly out of the way under the influence of its own weight against the tension of the relatively weak spring 88.

As the lever 30 tilts about its fulcrum 28 the treadle rod 60 will swing from a vertical to an inclined position and will exert upon the lever 30 not merely a straight downward pull, but a pull which includes a horizontal component. When the tilting movement of the lever 30 is arrested by the stop screw 110, continued downward movement of the treadle will cause this horizontal component to develop sufficiently to swing the lever 30 and the link 26 as a unit about the axis of the pin 24. Referring to Fig. 1, it will be seen that the axis of the pin 28 when the link 26 is in its initial or normal position is not only considerably above but is also somewhat rearward of the axis of the pin 24. The first effect therefore of the swinging movement of 75

the link 26 will be to raise the pad 48 slightly as the pad swings forwardly, increasing slightly the clearance between the bottom of the last and the edge of the upper at and near the heel end of the shoe as the pad 48 pushes the shoe forwardly. When the axis of the pin 28 is directly over the axis of the pin 24 the pad 48 will move horizontally forward, and the subsequent movement of the pad 48 will have a slight downward component. Fig. 1 indicates by dot-dash lines the initial positions of the shoe and of the last and by dash lines the positions of the shoe and of the forepart of the last when the operation has nearly been completed, the heel portion of the last at all times occupying its initial position. At the stage of the operation represented by dash lines the last is completely broken; the link 26 has swung forwardly almost to the extreme position determined by the hook 106; the heel end of the shoe has been raised clear of the last and the shoe has been pushed bodily forward until it is about ready to drop off the last. It will be noted also that at this stage of the operation the treadle rod 60 is no longer vertical but inclines rearwardly from its connection to the treadle to its connection to the bell crank 56. The length of the link 26 should be such as to provide an arcuate path for the pin 28 similar to the path which the shoe will naturally take as it is pushed forwardly off the broken last. A distance of about one foot from the axis of the pin 24 to the axis of the pin 28 will insure the desired path of travel.

Further depression of the treadle will bring the link 26 against the hook 106. The shoe is now free of the last and may be allowed to drop into a suitable receptacle or may be taken from the last by hand. The operator ordinarily before releasing the treadle will straighten out the broken last and remove it from the last pin. The last may, however, be left in position without interfering with the return of the various parts of the machine to their initial positions. Upon release of the treadle the spring 97 will first return the link 26. As soon as the extension 104 comes into engagement with the bumper 102 the lever 39 will return from tilted to horizontal position and the slide 40 will move rearwardly in its guideway. When the lever 39 engages the abutment 32 the spring latch 34 will snap into the notch 36 and the machine will be ready for another operation.

Having thus described my invention, what I claim as new and desire to secure by Letters Patent of the United States is:

1. A machine for separating shoes from lasts comprising a support for a last with a shoe thereon, a member engageable with the rear portion of the shoe, a member engageable with the forepart of the sole of the shoe, a carrier for said shoe-engageable members, and means for operating said carrier to cause the first-mentioned shoe-engageable member to raise the rear portion of the shoe relatively to the last and to cause the second-mentioned shoe-engageable member to break the last by pressure through the forepart of the sole of the shoe.

2. A machine for separating shoes from lasts comprising a support for a last with a shoe thereon, a member engageable with the rear portion of the shoe, a member engageable with the bottom of the forepart of the shoe, a lever upon which said shoe-engageable members are mounted, a fulcrum for said lever between said shoe-engageable members, and means for tilting said

lever about said fulcrum to cause the first-mentioned shoe-engageable member to raise the rear portion of the shoe relatively to the last and to cause the second-mentioned shoe-engageable member to break the last by pressure against the bottom of the forepart of the shoe. 5

3. A machine for separating shoes from lasts comprising a support for a last with a shoe thereon, a member engageable with the rear portion of the shoe, a member engageable with the forepart of the sole of the shoe, a lever upon which said shoe-engageable members are mounted, a fulcrum for said lever substantially coaxial with the hinge of the last, a treadle, and connecting means between said treadle and said 15 lever for tilting said lever about its fulcrum to cause the first-mentioned shoe-engageable member to raise the rear portion of the shoe relatively to the last and to cause the second-mentioned shoe-engageable member to break the last by 20 pressure against the bottom of the forepart of the shoe.

4. A machine for separating shoes from lasts comprising a support for a last with a shoe thereon, a friction pad engageable with the rear 25 portion of the shoe upper, a member engageable with the forepart of the sole of the shoe, a carrier for said pad and for said shoe-engageable member, and means for bringing said pad into frictional gripping engagement with the rear 30 portion of the shoe upper and operating said carrier to cause the pad to raise the rear portion of the shoe from the last and to cause the sole-engageable member to break the last.

5. A machine for separating shoes from lasts 35 comprising a support for a last with a shoe thereon, a lever, a friction pad mounted in said lever for relative movement thereto, a member carried by said lever and engageable with the forepart of the sole of the shoe, a fulcrum for 40 said lever, and means for moving said pad relatively to said lever to bring said pad into frictional gripping engagement with the rear portion of the shoe upper and for thereupon tilting said lever about its fulcrum to cause the pad to 45 raise the rear portion of the shoe from the last and to cause the sole-engageable member to break the last.

6. A machine for separating shoes from lasts comprising a support for a last with a shoe 50 thereon, a lever, a fulcrum for said lever, said lever having a longitudinal guideway positioned on one side of said fulcrum, a padded friction member mounted for movement in said guideway, a member carried by said lever on the other 55 side of said fulcrum for engaging the forepart of the sole of the shoe, a bell crank pivotally mounted on said lever, a connecting rod between said friction member and one arm of said bell crank, and operating means connected to the 60 other arm of said bell crank for rotating said bell crank to move said friction member into frictional engagement with the rear portion of the shoe upper, and then, when movement of the friction member is arrested by engagement with 65 the shoe, for tilting said lever about its fulcrum to cause the friction member to raise the rear portion of the shoe from the last and to cause the sole-engaging member to break the last by pressure transmitted through the sole of the shoe. 70

7. A machine for separating shoes from lasts comprising a support for a last with a shoe thereon, a member engageable with the rear portion of the shoe, a member engageable with the forepart of the sole of the shoe, a carrier for said 75

- shoe-engageable members, and means for operating said carrier first to cause the first-mentioned shoe-engageable member to raise the rear portion of the shoe relatively to the last and to cause 5 the second-mentioned member to break the last by pressure through the sole of the shoe and then, when the rear portion of the shoe has cleared the last, to cause the first-mentioned member to urge the shoe forwardly off the last.
- 10 8. A machine for separating shoes from lasts comprising a support for a last with a shoe thereon, a friction member engageable with the rear portion of the shoe, a member engageable with the forepart of the sole of the shoe, a lever 15 upon which said shoe-engageable members are mounted, a fulcrum for said lever between said shoe-engageable members, a movable support for said fulcrum, and means operable first to bring said friction member into frictional gripping engagement with the rear portion of the shoe upper, then to tilt said lever about its fulcrum to cause the friction member to raise the rear portion of the shoe from the last and to cause the sole-engageable member to break the 20 last, and then, when the rear portion of the shoe clears the last, to move said lever bodily with its fulcrum in a direction to urge the shoe forwardly off the last.
9. A machine for separating shoes from lasts 25 comprising a support for the heel end of a last with a shoe thereon, a shoe-removing tool, means for operating said shoe-removing tool first to engage the rear portion of the shoe, then to raise the rear portion of the shoe relatively to the last and then to push the shoe forwardly off the last, and means for breaking the last while said shoe-removing tool is raising the rear portion of the shoe relatively to the last.
10. A machine for separating shoes from lasts 30 comprising a support for the heel end of a last with a shoe thereon, a shoe-removing tool, means for operating said shoe-removing tool first to engage the rear portion of the shoe, then to raise the rear portion of the shoe relatively to the last and then to push the shoe forwardly off the last, and means for breaking the last while said shoe-removing tool is raising the rear portion of the shoe relatively to the last, said operating means being constructed and arranged to cause said shoe-removing tool when pushing the shoe forwardly off the last to travel in an arcuate path the curvature of which conforms generally to the shape of the broken last.
11. In a machine for separating shoes from lasts, a support for a last with a shoe thereon, a member engageable with the forepart of the sole of the shoe, resilient means for moving said sole-engageable member from an inoperative position into a position of engagement with the sole, and means for urging said sole-engageable member against the sole to break the last.
12. In a machine for separating shoes from lasts, a support for a last with a shoe thereon, a pad engageable with the forepart of the sole of the shoe, a pivotal support constructed and arranged to enable said pad to move in a direction generally lengthwise of the shoe but inclined to the forepart of the sole of the shoe, a spring for urging said pad about said pivotal support into engagement with the forepart of the sole of the shoe, and means for urging said pivotal support in a direction heightwise of the shoe to cause said pad to break the last.
13. A machine for separating shoes from lasts 75 comprising a support for a last with a shoe there-
- on, a lever mounted for tilting movement in a plane heightwise with respect to the shoe, a shoe-removing tool carried by said lever with provision for longitudinal movement relatively thereto, and operating means constructed and arranged first to move said shoe-removing tool longitudinally along said lever into operative engagement with the shoe and then to tilt said lever to cause the shoe-removing tool to urge the shoe off the last.
14. A machine for separating shoes from lasts comprising a support for a last with a shoe thereon, a lever mounted for tilting movement in a plane heightwise with respect to the shoe, said lever having a longitudinal guideway, a shoe-removing tool movable in said guideway, a bell crank fulcrumed upon said lever, a connecting rod between one arm of said bell crank and said shoe-removing tool, and an operating connection to the other arm of said bell crank whereby the force transmitted through said operating connection will serve first to rotate the bell crank until the shoe-removing tool comes into engagement with the shoe and then to tilt the lever to impart an inoperative movement to said shoe-removing tool.
15. A machine for separating shoes from lasts comprising a support for a last with a shoe thereon, a lever mounted for tilting movement in a plane heightwise with respect to the shoe, said lever having a longitudinal guideway, a slide in said guideway, a friction pad carried by said slide, a bell crank fulcrumed upon said lever, a connecting rod between one arm of said bell crank and said slide, a treadle, and a rod connecting the other arm of said bell crank to said treadle whereby operation of the treadle will first rotate said bell crank to bring said pad into frictional gripping engagement with the shoe and will then tilt the lever to cause the pad to urge the shoe off the last.
16. A machine for separating shoes from lasts comprising a support for a last with a shoe thereon, a lever mounted for tilting movement in a plane heightwise with respect to the shoe, said lever having a longitudinal guideway, a frictional shoe-removing tool movable in said guideway, a bell crank fulcrumed upon said lever, a connecting rod between one arm of said bell crank and said shoe-removing tool, operating means constructed and arranged to exert force upon the other arm of the bell crank tending to rotate the bell crank, and a spring latch tending to prevent tilting of said lever, said spring latch being constructed and arranged to yield to enable the lever to tilt in response to the force exerted by said operating means when rotation of the bell crank has been arrested by the shoe-removing tool engaging the shoe with frictional gripping pressure, such tilting of the lever serving to impart to the shoe-removing tool an operative movement tending to urge the shoe off the last.
17. A machine for separating shoes from lasts comprising a support for a last with a shoe thereon, a lever, a fulcrum upon which said lever is mounted for tilting movement in a plane heightwise with respect to the shoe, means for supporting said fulcrum for movement in a path generally lengthwise with respect to the shoe, a shoe-removing tool carried by said lever and movable longitudinally with respect thereto, and operating means constructed and arranged first to move said shoe-removing tool along said lever into operative engagement with the rear portion

of the shoe, then to tilt said lever about said fulcrum to cause the shoe-removing tool to move the rear portion of the shoe in a heightwise direction off the last, and then when the rear portion of the shoe has cleared the last to move said lever with its fulcrum bodily forward to cause said shoe-removing tool to push the shoe forwardly off the last.

18. A machine for separating shoes from lasts comprising an upstanding last pin for supporting in inverted position a last with a shoe thereon, a lever, a fulcrum upon which said lever is mounted for heightwise tilting movement, a link upon which said fulcrum is mounted for arcuate movement, a pivotal bearing for said link located below the position occupied by a last on said last pin, a shoe-removing tool carried by said lever and movable longitudinally with respect thereto, and operating means constructed and arranged first to move said shoe-removing tool along said lever into operative engagement with the rear portion of the shoe, then to tilt said lever about said fulcrum to cause the shoe-removing tool to move the rear portion of the shoe upwardly off the last, and then when the rear portion of the shoe has cleared the last to move said lever and its fulcrum bodily forward in an arcuate path about the pivotal bearing of said link to cause said shoe-removing tool to push the shoe forwardly off the last.

19. A machine for separating shoes from lasts comprising a support for a last with a shoe thereon, a friction pad engageable with the rear portion of the shoe, operating means constructed and arranged to exert upon the pad a force having a forward and a heightwise component relatively to the shoe, and yieldable means for holding said pad from movement under the influence of said heightwise component until said forward

component has caused said pad to bear with frictional gripping pressure against the shoe, whereupon said yieldable means will release said pad to the influence of said heightwise component which will then cause the pad to move the rear portion of the shoe off the last.

20. A machine for separating shoes from lasts comprising a support for a last with a shoe thereon, a shoe-removing tool constructed and arranged for movement in one direction from an inoperative to an operative position and for an operative movement in a different direction, operating means constructed and arranged to exert upon said tool a force having components in each of said directions, and means for constraining movement of said tool under the influence of said force to the first-mentioned direction until the tool has arrived at operative position and for thereupon releasing said tool to the influence of the component of force in the second-mentioned direction to enable the tool to perform on operative movement.

21. A machine for separating shoes from lasts comprising a support for a last with a shoe thereon, a shoe-removing tool constructed and arranged for movement in one direction from an inoperative to an operative position and for an operative movement in a different direction, operating means constructed and arranged to exert upon said tool a force having components in each of said directions, and a latch for holding said tool against movement in the second-mentioned direction until said tool under the influence of said force has arrived at operative position, said latch being constructed and arranged thereupon to release said tool for operative movement in the second-mentioned direction.
